[57] CLAIM

The ornamental design for a vehicle van corner cap member, as shown and described.

DESCRIPTION

FIG. 1 is a perspective view of a vehicle van corner cap member showing my new design, with right and left hand embodiments illustrated in their positions of use, the portions shown in phantom lines being for illustrative purposes and forming no part of the claimed design; FIG. 2 is an enlarged front elevational view of the left hand embodiment illustrated in FIG. 1;

FIG. 3 is an enlarged front elevational view of the right hand embodiment illustrated in FIG. 1;

FIG. 4 is a side elevational view as seen from the left, in FIG. 2;

FIG. 5 is a side elevational view as seen from the right in FIG. 2;

FIG. 6 is a top plan view of FIG. 4;

FIG. 7 is a bottom plan view of FIG. 6; and

FIG. 8 is a rear elevational view of FIG. 2.

FIG. 1.

FIG. 3.

FIG. 2.

*FIG. 4.**FIG. 5.*

FIG. 6.

FIG. 7.

FIG. 8.
